UNITED STATES PATENT OFFICE.

BRUCE C. WHITE, OF NEW YORK, N. Y., ASSIGNOR TO R. HOE AND CO., OF NEW YORK,
N. Y., A CORPORATION OF NEW YORK.

INKING MECHANISM FOR PRINTING-MACHINES.

1,311,198.

Specification of Letters Patent. Patented July 29, 1919.

Application filed July 7, 1915. Serial No. 38,528.

To all whom it may concern:

Be it known that I, BRUCE C. WHITE, a citizen of the United States, residing at New York, county of New York, and State 5 of New York, have invented certain new and useful Improvements in Inking Mechanism for Printing-Machines, fully described and represented in the following specification and the accompanying drawings, forming a 10 part of the same.

This invention relates to an improved inking mechanism for printing machines of that type in which the ink is forced by pumps to the distributing cylinder or other 15 portion of the inking apparatus so as to supply the ink under pressure and in regulated quantity and preferably so that the supply of ink to each column or other section of the form may be varied as desired 20 in accordance with the matter to be printed.

The special object of the invention is to provide a more efficient and satisfactory apparatus for thus supplying the ink and regulating the supply from a convenient 25 point and without interrupting the operation of the machine, and to secure greater certainty and uniformity in the supply and distribution of the ink.

With these objects in view, the invention 30 includes various novel features, constructions and combinations of parts in inking mechanism, and a novel pump designed especially for such use, but applicable also to other uses and for pumping other fluids.

35 For a full understanding of the invention, a detailed description of an inking mechanism embodying the invention in its preferred form, and a modified form of pump, will now be given in connection with 40 the accompanying drawings forming a part of this specification, and the features forming the invention then specifically pointed out in the drawings.

Figure 1 is a diagrammatic side elevation 45 of a multiple web printing press equipped with inking mechanism embodying the invention;

Fig. 2 is an enlarged diagrammatic plan view of one of the distributing cylinders. 50 and its ink supply mechanism;

Fig. 3 is a side elevation of Fig. 2;

Fig. 4 is a plan view of the ink supply reservoir with the cover broken away to show the ink supply mechanism;

55 Fig. 5 is a vertical section through the

ink supply reservoir taken on the irregular line 5—5 of Fig. 4;

Fig. 6 is a cross section on the line 6—6 of Figs. 4 and 5;

Fig. 7 is a horizontal section of one end 60 of the ink supply reservoir on the lines 7—7 of Fig. 6; parts being omitted;

Fig. 8 is a vertical section through one 65 of the delivery nozzles;

Fig. 9 is a face view of a portion of the 70 delivery nozzles looking to the left in Fig. 8;

Fig. 10 is a section on the line 10 of Fig. 8;

Fig. 11 is a view similar to Fig. 8 showing 75 a modification;

Fig. 12 is a horizontal section through the 70 ink supply reservoir showing a modified construction of ink supply and regulating means;

Fig. 13 is a vertical section on the line 13—13 of Fig. 12;

Fig. 14 is a vertical cross section of the 75 ink supply reservoir on the line 14—14 of Figs. 12 and 13;

Figs. 15 and 16 are partial views similar 80 to Fig. 14, but showing the parts in different positions.

Fig. 17 is a plan view, partly broken away, of the feed shown in Fig. 11.

Referring now to the drawings, the invention is shown in Fig. 1 as applied in 85 connection with a five web press having rotary printing couples, each couple consisting of the form cylinder A and impression cylinder B, the form cylinder A taking the ink from form rollers *a* supplied from distributing cylinder C having the usual vibrating ink distributing rolls *c*. This is a common type of such printing machines, but it will be understood that this is shown only for purpose of illustration and that 95 the invention is equally applicable to other types of printing machines, either reciprocating or rotary, and with any desired type of ink distributing mechanism.

In accordance with the present invention, 100 ink is supplied to the distributing cylinders C from groups of ink delivery nozzles grouped in casings D and supplied with ink through conduits or supply pipes E from the supply reservoirs F containing the 105 pumps, and the supply reservoirs are shown in Fig. 1 as supplied with ink from tank G through branch pipes H connecting with circulating pipe I, through which ink is continuously circulated from tank G by any 110

suitable means, as, for instance, by the rotary pump K, indicated in Fig. 1, so that the supply of ink in reservoirs F is constantly maintained under control of a float valve, as 5 hereafter described, the branch pipes H for the separate supply reservoirs F preferably being provided with cocks, as shown, so as to cut out of the inking system any supply reservoirs desired when their printing couples 10 are not used. As shown, the supply reservoirs and nozzle casings may readily be supported in proper position by simply bolting to the press frame.

The preferred general arrangement of the 15 supply reservoirs, conduits or supply pipes E and nozzle casings D, are shown in Figs. 1 to 3, the whole inking apparatus occupying but a small space at the side of the distributing cylinders, so as not to substantially 20 interfere with the desired access to the press, and the supply reservoirs being conveniently placed for access and adjustment of the ink supply, without interfering with the operation of the machine.

25 The construction and operation of the ink pumping and regulating apparatus within the supply reservoirs F, and of the nozzles for delivering the ink to the distributing cylinders, are duplicates, each of these being as follows: The interior of the supply 30 reservoir F is partially filled with ink, in which work the ink pumps by which the ink is forced downward through the conduits or supply pipes E, which are packed in openings formed in the bottom of the reservoir. A single acting pump, having vertically acting plunger 10, is provided for each desired 35 section of the form, usually a column, two parallel rows of these pumps being shown, the pump chambers for these pumps being formed in bars 11 extending lengthwise of the reservoir F and united by cross bars 12 to form a frame open between the bars 40 11 to receive shaft 13 carrying eccentric 14, by which the frame, with its pump cylinders and plungers, is moved sidewise and the plungers 10 reciprocated, the eccentric 14 securing this sidewise movement of the frame 45 through action on yokes on cross bars 12 of the moving frame, and the vertical movement through action on vertical bars 15 mounted to slide vertically in these yokes while held from sidewise movement therein. 50 These bars 15 form downward extensions of a bar 16 extending longitudinally of the reservoir above the pumps and which has arms 17 extending over the pump plungers 10 so as to engage and operate the latter on the 55 downward movement of the plate bar 16. This bar 16 also carries arms 18 extending on opposite sides of the bar, which arms carry pivot shaft 19 on which are loosely 60 mounted rock arms 20, one for each plunger, 65 having toes 21 extending inward under

flanged heads 1 of plungers 10, and these arms 20 are formed of a sleeve and inclosed sliding stem, so as to be extensible and spring-pressed apart by spring 22, the sleeve having a head 23 numbered to correspond 70 with the column or section of the form supplied by its pump, and the sleeve being provided with a catch 2 adapted to engage teeth 3 for holding the rock arm in adjusted position, these teeth 3 being formed in the underside of arms 24 projecting in opposite directions from central web 25 extending upward from bar 16, the arms 24 preferably being made separately and secured in slots in the web 25 by a cover bar 26, as shown. The ends of the arms 24 are tied together by rods 27 with spacing sleeves between the arms so as to form the parts carried by bar 16 into a frame that reciprocates vertically in the frame formed by bars 11 and cross bars 12 80 and moves sidewise with the latter frame.

85 The shaft 13 may be driven by any suitable means, but as shown is driven by gear 28 and intermediate 29 from gear 30 on sleeve 31 loose on driving shaft 32 and carrying disk 33 having handle 34 mounted therein, this handle 34 having a point 35 entering a recess in disk 36 keyed to shaft 32, so as to clutch disk 33 and sleeve 31 to the shaft for driving the pumps when the handle 34 is thrown into the position shown in Fig. 7, while by rocking handle 34 outward against its holding spring into the position shown in Fig. 4, sleeve 31 is released from shaft 32, and the pumps can then be run by hand at the speed desired for testing, cleaning or repair, or cleaning fluid may be run through the pumps and pipes, if desired. The driving shaft 32 may be driven from the distributing cylinder or other part of the press by any suitable gearing so as to secure the proper speed, or may be driven by separate motor, if preferred.

100 The ink is preferably maintained at the desired level in the reservoir F by float control, the inlet pipe H being controlled by valve 36 under the control of float lever 37 and float 38, which parts may be of any suitable construction. Circulation of ink 105 from the side of the pump frame at which supply pipe H enters is provided for by passages 39 connecting side troughs 40 with a central trough 41, with which connects a drain pipe 42, provision thus being made 110 for draining the reservoir from troughs 40, 41, in which any sediment or thickened ink 115 will collect and for washing the reservoir by running water or cleaning fluid therethrough. The reservoir is preferably provided with a hinged cover 43, as shown, by raising which access is had to all the heads 120 23 of the adjusting arms 20 for varying the supply of ink to any column or columns of 125 the form.

The conduits or supply pipes E from the reservoir F have their delivery ends arranged in line along the distributing cylinder C, being grouped in casing D, as shown in Figs. 8 and 10, this casing D being provided with a removable cover 44 for access to the pipes, and the wall 45 of the casing adjacent to the distributing cylinder having openings therethrough receiving the ends of the pipes and through which the ink passes to the nozzles supplying the distributing cylinder.

In the construction shown in Figs. 8 to 10, these nozzles deliver through the ports in support plate 45 into narrow passages 46 outside plate 45, by which the ink is distributed sidewise from the pipes to substantially the extent of a column or other section to be supplied with ink by the pipe, and these passages have small delivery orifices 4, of unobstructed circular or other polygonal form, a sufficient number of which are formed on each passage to secure the distribution required, and the ink from these openings falls down the inclined face 5 of a bar or nozzle piece 47 mounted on the outer side of plate 45 and acting to form the outer wall of passages 46, previously described, and to divide these passages from each other.

The inclined surface 5 extends substantially into contact with the distributing cylinder C, and the ink from the orifices 4 spreads in flowing down the incline so as to form a continuous thin layer or film of ink in contact with the distributing cylinder. The small orifices or passages 4, through which the ink is distributed from passages 46, preferably extend upward, as shown, so as to assure their being constantly filled with ink and prevent the entrance of air from outside, as might be the case if they were directed downward from passages 46.

In Fig. 11 there is shown a modified construction, especially adapted for the heavy ink used in magazine, book and similar work, in which the ink is blown by an air current from the ends of the passages 4 onto the distributing cylinder, which it is found in practice secures a better distribution of such ink. The air current or air blast, is shown as provided by an air blast pipe 48 mounted on top of the casing cover 44 and having a suitable contracting nozzle 6 delivering a continuous air jet, or series of jets, just behind the orifices 4. With this construction, also, the incline 5 is preferably used and acts, as in Figs. 8 and 9, to distribute sidewise, from orifices 4, any ink not forced by the air blasts onto the distributing cylinder.

The casing D is preferably adjustable toward and from the distributing cylinder C, so as to secure the best position for the re-

ceipt of the ink from the nozzles by distributing cylinder C, and for this purpose, is shown as carried by bolts 49 secured to the press frame and having adjusting nuts 50, between which arms 51, carrying the casing, are mounted on the bolts. Preferably, springs 52 are used outside the arms 51, permitting the casing to yield slightly. The ink reservoir F, with the supply ends of the pipes E connected thereto, is carried by the casing D so as to move therewith, being shown in Fig. 2 as bolted to a bracket 53 on one of the arms 51 on the casing D.

The operation of the inking mechanism will be clear from the drawings and above description with the following brief explanation.

The ink from supply tank G is circulated through pipe I by pump K and the supply reservoirs F kept full to the required level by the float control of branch pipes H, so that a constant suction supply to the pumps is thus maintained. The pump chambers formed in blocks 11 and in which the pump plungers 10 move are brought by eccentric 14 alternately into connection with the reservoir on the upward or suction stroke of the plungers 10 and into line with the ports in the reservoir bottom connecting with pipes E for the downward or delivery stroke of the plungers, and the vertical movement of the bar 16 and plunger operating parts carried thereby is secured in proper time by the eccentric 14. A measured quantity of ink is thus delivered by each pump under fixed pressure at each stroke of the plungers 10. These valveless pumps aid materially in assuring the proper action of the pumps and their delivery of a fixed quantity of ink, and avoid the difficulties incident to handling ink with valved pumps.

As described above, the lift of each plunger 10 on the suction stroke is determined by the position of its rocking arm 20 which determines the time of engagement of toe 21 with plunger head 1, and the position of the arms 20 is readily adjusted by moving the numbered heads or finger pieces 23 sidewise. The arrangement of the adjusting heads so that they move sidewise in adjusting the ink supply to the different columns or sections, is such that the relative position of the heads and consequent relative ink supply to the different columns or sections is readily seen, and by arranging the heads so that they are normally in line for equal adjustment of ink for the different columns or sections, a glance at the top of the inking mechanism on raising the cover 43 shows the relative inking of all parts of the page or pages supplied by the reservoir. This is clear from Fig. 4, in which the reservoir is illustrated as supplying four pages of eight columns each with the inking mechanism adjusted for equal

supply to all columns on two pages, and adjusted for varying the supply to different columns of the other two pages. This arrangement of sidewise moving adjusting heads or finger pieces placed closely adjacent, also enables the heads for a page or any number of columns thereof, to be adjusted simultaneously by a single movement of the hand, which is convenient for quick and uniform adjustment.

In Figs. 12 to 16 there is shown a slightly modified construction of pumps and regulating means, the other parts of the apparatus being the same as above described. In this case the plungers 10 and the blocks 11 containing the pump chambers of the two sets are actuated by separate eccentrics, the two blocks 11 being connected by cross plates 54 at opposite ends, which are vertically slotted to receive sliding blocks 55 carrying eccentric sleeves 56 in which run eccentrics 57 on shafts 58, so that the rotation of the eccentrics moves the blocks 55, with the frame formed by plates 54 and bars 11, sidewise, and moves the blocks 55, with their eccentric sleeves 56, vertically. The pump plungers 10 carry yokes 59, the upper ends of which are threaded on adjusting screws 60 having finger pieces 61 extending upward into convenient position for access when the cover is lifted and preferably held in any adjusted position by springs 62 engaging the knurled side of the finger pieces. The adjusting screws 60 carry heads 63 engaging the eccentric rings 56 to raise the plungers 10 the length of the suction stroke or lift of the plungers, the amount of ink delivered thus being regulated by the position of the screws 60, which determines the lift of the yokes 59 and plungers 10 by the eccentrics. The eccentric shafts 58 may be rotated by any suitable means, but are shown as geared together by gears 64 operated by gear 65 on shaft 66, which in turn is driven through bevel gears 67 from driving shaft 68 outside the reservoir F, and actuated from the press or otherwise in any suitable manner.

In this construction there is shown, also, a convenient means for cutting out a whole page of the inking, or such part thereof as the construction may be designed for, by a single valve, which arrangement also is readily applicable to the construction shown in Figs. 1 to 11, and above described. For this purpose each row of the conduits or supply pipes E connects with a circular valve chamber in which is mounted a rotating valve 69 extending over the whole row of conduits E, or such part thereof as desired, and accessible from outside the reservoir for rotation, as by the squared head 70, shown in Fig. 13. These valves 69 have transverse ports 7, and the bottom plate of the reservoir F is provided with two

passages 8, 9, one connected with the pump chamber and the other with the reservoir, so that by turning a valve 69 into the position shown in Figs. 14 and 15, the pumps in the row corresponding to the valve will deliver ink from the chamber through ports 8, 7, into the conduits or supply pipes E, and by turning the valve into the position shown in Fig. 16, the pumps of its row will be closed to pipes E, and the ink be circulated through ports 8, 7, 9, from the pump to the reservoir on the discharge stroke. The simple rotation of a valve 69, therefore, will cut out a page, or such portion of the inking as the apparatus may be designed for, without interfering with the adjustment of the separate pumps.

The operation of the construction shown in Figs. 12 to 16 will be substantially the same as that described in connection with Figs. 1 to 11, except as will be understood from the drawings, so that no further description of operation is required.

While the construction illustrated and described is one which is effective for carrying out the invention, and preferably used with presses of the type shown, it will be understood that changes may be made in the construction and arrangement of the devices shown, in accordance with the character of press with which the inking mechanism is used and the results desired, while retaining the invention defined by the claims.

What is claimed is:

1. In an inking mechanism for printing machines, the combination with a plurality of separate ink conduits, one for each column or section of the form, and an ink pump for each conduit, of means for regulating the ink supply delivered by each pump independently of the others, said regulating means including an adjusting member for each pump movable sidewise for regulating the ink supply.

2. In an inking mechanism for printing machines, the combination with a plurality of separate ink conduits, one for each column or section of the form, and an ink pump for each conduit, of means for regulating the ink supply delivered by each pump independently of the others, said regulating means including a manually operated adjusting member for each pump movable sidewise for regulating the ink supply, the adjusting members for the different pumps being arranged side by side and closely adjacent.

3. In an inking mechanism for printing machines, the combination with a plurality of separate ink conduits, one for each column or section of the form, and an ink pump for each conduit, of means for regulating the ink supply delivered by each pump independently of the others, said regulating

- means including a manually operated adjusting member for each pump movable sidewise for regulating the ink supply, the adjusting members for the different pumps 5 being arranged in line for similar adjustment of ink supply and movable out of line for varying the pump supply to the different pumps.
4. In an inking mechanism for printing machines, the combination with a plurality of separate ink conduits, one for each column or section of the form, and means for supplying ink to each conduit, of means for regulating the ink supply to each conduit independently of the others, said regulating means including a manually operated adjusting member for each conduit movable sidewise for regulating the ink supply, the adjusting members being arranged side by 20 side.
5. In an inking mechanism for printing machines, the combination with a plurality of separate ink conduits, one for each column or section of the form, and an ink 25 pump for each conduit, of means for regulating the ink supply delivered by each pump independently of the others, and a single valve controlling the delivery of a plurality of said conduits whereby the supply of ink to a page or other portion of the 30 form may be cut out or controlled independently of the individual adjustment of each pump.
6. In an inking mechanism for printing machines, the combination with a plurality 35 of supply reservoirs, a series of ink pumps supplied from each reservoir, and separate ink delivery conduits for the pumps, one pump and conduit for each column or section 40 of the form, of a supply common to the reservoirs, a pump and circulating pipe for constantly circulating ink from the common supply, branch pipes from said circulating pipe for the supply reservoirs, and 45 means for automatically controlling the supply of ink to each supply reservoir.
7. In an inking mechanism for printing machines, the combination with a plurality of supply reservoirs, a series of ink pumps 50 supplied from each reservoir, and separate ink conduits for the pumps, one pump and conduit for each column or section of the form, of a supply common to the reservoirs, a pump and circulating pipe for circulating 55 ink from the supply, branch pipes from said circulating pipe for the supply reservoirs, and float controlled means for automatically controlling the supply of ink to each reservoir to maintain the level of ink therein.
8. In an inking mechanism for printing machines, the combination with an ink supply reservoir, of a plurality of independent ink delivery conduits, and a plurality of valveless plunger pumps in the supply reservoir, 60 one for each conduit, and means for regulating the amount of ink supplied by each pump independently of the others.
9. In an inking mechanism for printing machines, the combination with an ink supply reservoir, of a plurality of independent ink delivery conduits, a plurality of valveless plunger pumps in the supply reservoir, one for each conduit, each pump having a pump chamber movable sidewise for suction and discharge, and means for moving the 70 pump chambers and operating the plungers.
10. In an inking mechanism for printing machines, the combination with an ink supply reservoir, of a plurality of independent ink delivery conduits, a plurality of valveless plunger pumps in the supply reservoir, one for each conduit, each pump having a pump chamber movable sidewise for suction and discharge, means for moving the pump chambers and operating the plungers, and 75 means for varying the stroke of each plunger independently of the others to vary the amount of ink delivered by the pumps.
11. In an inking mechanism for printing machines, the combination with an ink supply reservoir, of a plurality of ink delivery conduits, a plurality of valveless plunger pumps in the supply reservoir, one for each conduit, each pump having a pump chamber opening at the end in the line of movement of the plunger, and means for moving the pump chamber sidewise to bring the end opening into connection alternately with the reservoir for suction and with the conduit 80 for discharge.
12. In an inking mechanism for printing machines, an ink delivery nozzle having a series of small unobstructed polygonal ink delivery openings, and a distributing incline over which the ink flows from the openings 85 for distributing the ink sidewise.
13. In an inking mechanism for printing machines, an ink delivery nozzle having a series of small ink delivery openings, and an air blast device arranged to deliver an air current across the outlet ends of the openings 90 for blowing the ink from said openings on to the ink receiving member.
14. In an inking mechanism for printing machines, an ink delivery opening, an air blast device arranged to deliver an air current across the outlet end of the opening for blowing the ink from said opening onto the ink receiving member, and means for distributing the ink received from said opening. 95
15. In an inking mechanism for printing machines, an ink delivery nozzle, an air blast device for blowing the ink from said nozzle on to the ink receiving member, and a distributing incline below the nozzle.
16. In an inking mechanism for printing machines, an ink delivery nozzle having a series of small ink delivery openings, an air blast device for blowing the ink from said 100 nozzle.

openings on to the ink receiving member, and a distributing incline below the plane of the air blast.

17. In an inking mechanism for printing machines, the combination with the ink conduits E arranged side by side for supplying different columns or sections of the form, of chambers 46 supplied by said conduits and having a series of small unobstructed polygonal upwardly extending openings 4 through which the ink is delivered, and an incline 5 below the openings for distributing the ink sidewise.

18. In an inking mechanism for printing machines, a series of ink delivery nozzles for supplying different columns or sections of the form, and a support for said nozzles adjustable toward and from the ink receiving member and yieldingly mounted for movement toward and from the ink receiving member.

19. In an inking mechanism for printing machines, a series of ink delivery nozzles for supplying different columns or sections 25 of the form, a support for said nozzles adjustable toward and from the ink receiving member and yieldingly mounted for movement toward and from the ink receiving member, and a supply reservoir with ink 30 pumps therein mounted to move with the nozzle support, and ink conduits connecting the pumps and nozzles.

20. A printing press including in combination a form cylinder, an ink drum, and 35 means for supplying atomized ink to said drum, said means including an atomizing device and a pump presenting intermittently thereto minute globules of ink.

21. A printing press including in combination a form cylinder, an ink drum, and

means for supplying atomized ink to said drum in variable quantities therealong, said means including an atomizing device and a pump presenting intermittently thereto minute globules of ink.

22. A printing press including in combination a form cylinder, an ink drum, and means for supplying atomized ink to said drum in variable quantities thereabout, said means including an atomizing device and a 50 pump presenting intermittently thereto minute globules of ink.

23. A printing press including in combination a rotating ink receiving cylinder, means for supplying ink thereto comprising 55 a plurality of air nozzles, arranged therealong and means for supplying ink thereto comprising external ink nozzles and positively operating ink supplying means.

24. A printing press including in combination a rotating ink receiving cylinder, means for supplying ink thereto comprising a plurality of air nozzles arranged therealong, means for supplying ink thereto comprising an ink nozzle for each air nozzle and 60 a positively acting ink pump.

25. In combination in a printing press, a rotating ink-receiving cylinder, a plurality of pneumatic ink atomizing nozzles supplying ink thereto, an externally located ink 70 supplying nozzle for each atomizing nozzle and a pump supplying intermittently a globule of ink to each ink nozzle.

In testimony whereof I have hereunto set my hand in the presence of two subscribing 75 witnesses.

BRUCE C. WHITE.
